DOORFRAME

Filed March 25, 1929

UNITED STATES PATENT OFFICE

ISAAC A. BAUM, OF CHICAGO, ILLINOIS

DOORFRAME

Application filed March 25, 1929. Serial No. 349,634.

My invention relates to door frames and particularly to an improved buck having numerous advantages hereinafter described.

An object of the invention here described is to provide a metal buck adapted to receive nailing blocks for supporting a jamb, the construction being such that added strength and stability are secured. These advantages are present by reason of peculiarities in design; for example, the depth of the channel-shaped buck is reduced, thereby reducing the distance between the jamb and the edge of the masonry wall. This lessens the extent of overhand and shortens the leverage tending to separate the buck from the wall under laterally exerted blows.

The rigidity of the structure is increased also by providing a double thickness of metal at the sides of the channel. The strength of the channel is also increased by eliminating cutout portions ordinarily provided in the web of the channel, the lateral positioning of the channel being secured by means of continuous strips.

By reducing the depth of the channel, the size of the wood blocks is correspondingly reduced with a saving of material.

Additional strength against lateral blows is provided by utilizing continuous strips from top to bottom of the channel instead of the usual ears arranged in spaced relation.

Inasmuch as the projecting or exposed portions of the buck should be painted and as paint will not adhere to black or blue iron sheets, it is essential that these portions be galvanized or similarly coated. By reason of the construction shown the channel member may be galvanized, whereas the strips may be of black iron.

Another advantage is that the plaster may, by reason of the simple expedient utilized by me, firmly anchored to the strips thus adding to the rigidity of the entire structure.

The invention will be more readily understood by reference to the accompanying drawings, in which

Fig. 1 is a perspective sectional view of a frame arranged in accordance with my invention;

Fig. 2 is a transverse sectional view therethrough; and

Fig. 3 is a fragmentary sectional view of a modification of the construction.

In the drawings, the masonry wall is indicated at 10, the jamb at 11 and the wood nailing blocks at 12. The buck is of channel form comprising a web 13 and flanges 14. The margins 15 of the flanges project at right angles and constitute plaster terminals. The channel portion may be formed of galvanized material to adapt the exposed portions to receive paint.

Continuous strips 16 of black iron are placed as shown and welded to the flanges of the channel. Nails 17 project through the two thicknesses of metal and hold the wood blocks. Other nails 18 are used for securing the jamb to the nailing blocks.

The strips at their rearward edge project a substantial distance beyond the limits of the channel and closely fit the masonry wall. As a means for anchoring the plaster to the strips, I strike out loops 19, these being arranged in suitable closely spaced relation to accomplish the desired result. Wall anchors 20 having hooked ends that engage in the apertures formed by striking out the loops, serve to hold the structure in place.

In the modification shown in Fig. 3 the buck comprises a web 21 and flanges 23 which may be formed of black iron, the strip 23 has the margins 24 forming a plaster terminal and may be of galvanized metal. Otherwise the construction is the same and the function is the same as that already described.

Obviously the construction is capable of some modification and I do not wish to be limited except as indicated in the appended claims.

I claim:

1. In frame construction, the combination of a channel shaped buck, and a continuous strip welded to a flange of the channel and extending rearwardly a substantial distance beyond the limits of the channel in line with the flange, and plaster anchors formed in said strip.

2. In door frame construction, the combination of a buck of relatively shallow chan-

nel construction, adapted to be mounted with the flanges projecting into the door opening, a wood member in the channel adapted to receive a jamb, and a flat, longitudinally continuous strip permanently secured to the outer face of a channel flange with the inner edge of the strip projecting a substantial distance beyond the limits of the channel and adapted to lie alongside of a wall.

5 3. In a door frame, the combination of a relatively shallow channel with the margins of the flanges bent to provide plaster terminals, and longitudinally continuous flat strips welded to the outside faces of the flanges of the channel and projecting rearwardly from the limits of the channel.

10 4. In a door frame, the combination of a relatively shallow channel with the margins of the flanges bent to provide plaster terminals, and longitudinally continuous flat strips welded to the outside faces of the flanges of the channel and projecting rearwardly from the limits of the channel, and plaster anchors formed in said strips.

15 5. In a door frame, the combination of a relatively shallow channel with the margins of the flanges bent to provide plaster terminals, and longitudinally continuous flat strips welded to the outside faces of the flanges of the channel and projecting rearwardly from the limits of the channel, and loops struck out from said strips to serve as plaster anchors.

20 6. In a door frame, the combination of a relatively shallow channel with the margins of the flanges bent to provide plaster terminals, and longitudinally continuous flat strips welded to the outside faces of the flanges of the channel and projecting rearwardly from the limits of the channel, wood members in said channel and a jamb secured to the wood members.

25 In testimony whereof I have affixed my signature.

ISAAC A. BAUM.
